UNITED STATES PATENT OFFICE.

ROBERT BAYLES ARMSTRONG, OF NEWCASTLE-UPON-TYNE, ENGLAND, ASSIGNOR TO HIMSELF AND R. & W. HAWTHORN LESLIE & COMPANY, LIMITED, BOTH OF NEWCASTLE-UPON-TYNE, ENGLAND.

WATER-TUBE STEAM-BOILER.

1,383,590.

Specification of Letters Patent.

Patented July 5, 1921.

Application filed December 7, 1918. Serial No. 265,781.

To all whom it may concern:

Be it known that I, ROBERT BAYLES ARMSTRONG, a subject of the King of Great Britain and Ireland, residing at Newcastle-upon-Tyne, in the county of Northumberland, England, have invented Improvements in Water-Tube Steam-Boilers, of which the following is a specification.

This invention has reference to water tube 10 boilers of the type comprising upper and lower vessels connected by generating tubes.

It has been proposed to provide such boilers with steam drums subdivided by partitions and with superheating tubes which 15 connect the several compartments thereof to a water drum, the connections of the steam and water drums being such that when superheating is desired, the steam can pass from a compartment of the steam drum, 20 through the superheating tubes to another compartment of the drum and thence to the steam outlet and that at other times water can be admitted to the superheating tubes. It has also been proposed to provide the 25 steam drum of a superheater with a partition which subdivides it into longitudinal steam inlet and superheated steam outlet compartments that are connected by depending U shaped superheating tubes and to 30 hinge the upper part of the partition so that it can be turned down into proximity to the lower part so that by flooding the tubes by raising the water level in the boiler the said tubes can be converted into generating tubes.

Now according to the present invention, subdivided steam drums are provided with valved connections whereby the steam spaces of the compartments can be placed in direct 40 communication and water admitted to the superheating tubes by which arrangement all the superheating tubes can be made to serve as generating tubes and the saturated steam generated passed from all the compartments to the ordinary steam outlet. The steam drums preferably are divided into longitudinal compartments so that there is a downward flow of steam in some of the superheater tubes throughout the full length 45 of the bank and upward flow in the remainder.

Boilers of the type comprising two lower water drums with furnace between them and two upper steam and water drums parallel

thereto but nearer together and connected 55 by steam pipes to a common steam drum between them, and having each lower drum connected to the opposite upper drum by transverse rows of inclined generating tubes crossing beneath the steam drum above the 60 center of the furnace, may have the common steam drum divided into longitudinal compartments which are connected by superheating tubes which lie over the one set of generating tubes and cross the other set. 65

Referring to the accompanying drawings Figure 1 shows in transverse section, with parts in elevation one construction of boiler embodying the invention;

Fig. 2 is, as to the left hand half, a section 70 on the line 2—2 Fig. 1 and, as to the right hand half, an elevation with the casings removed.

Fig. 3 is a diagrammatic view showing one 75 way of interconnecting the valve *k* and the valves *m* by chains passing around sprocket wheels fixed to the several valve spindles so that all must turn together in the same direction.

In this construction, there are two lower water drums *a* with furnace between them and two upper steam and water drums *b* parallel thereto but nearer together and connected by steam pipes *c* to a common steam drum *d* between them, each lower drum *a* being connected to the opposite upper drum *b* by transverse rows of inclined generating tubes *e* crossing beneath the steam drum above the 80 center of the furnace, the rows being alternately inclined in opposite directions; above 85 each lower water drum *a* is a smaller drum *f* with transverse rows of inclined superheating tubes *g* extending therefrom to the lower side of the steam drum *d*, these tubes in the example lying over the one set of transverse 90 rows of tubes and crossing the other set. The steam drum is divided by two or more longitudinal partitions *h* preferably bulged slightly inward into three or more compartments, each partition being arranged to cut 100 off the upper ends of some of the corresponding set of superheating tubes *g* from the others and to cut off the steam pipe connection *c* with the corresponding steam and water drum *b* from the middle compartment, 105 which may be provided with a steam outlet, as shown in Figs. 2 and 3; the two steam pipe connections *c* are provided with a by-

pass connection *i* to the front of the middle compartment of the steam drum, said by-pass connection being fitted with a stop valve *h* or valves. The small drums *f* at the 5 lower ends of the superheating tubes are respectively connected by pipes *l* at the front ends to the water drums *a* beneath them through stop valves *m*. Upon portions of each set of generating and superheating 10 tubes are baffles *n*, or the like; the baffles may be arranged in various ways according to the course the gases are to be caused to follow; in the example the baffles are arranged to close the alternate spaces between 15 the upper tier of tubes at their lower parts so as to check the flow of gases and direct them through the remaining spaces. *o* are water tubes arranged to form a wall and serving as downcomer tubes.

20 When raising the steam the stop valves *h* and *m* are open and the superheating tubes *g* then act as additional generating tubes; when it is desired to superheat the steam the stop valves *h* and *m* are closed, saturated 25 steam then passing from each outer compartment of the steam drum through those of the superheating tubes *g* in communication with it and returning from the small drum *f* below through the remainder of that set 30 of superheating tubes to the middle compartment of the steam drum.

All the stop valves are or may be interconnected so as to be opened and closed together.

35 Fig. 3 is a diagram illustrating one way of interconnecting the valve *h* and the valves *m* by a chain passing around sprocket wheels fixed to the several valve spindles so that all must turn together in the same direction.

40 As will be understood the construction of boiler just described is an example only of applying the invention which can be carried out in various ways.

What I claim is:—

45 1. In a water tube boiler, a superheater comprising an upper steam drum, two lower

drums, fixed longitudinal partitions dividing said upper drum into three compartments, banks of tubes connecting each of said lower drums with the upper drum, some 50 of each bank of tubes connecting at their upper ends with an outer compartment and some with the middle compartment, a steam inlet connection to each outer compartment, a steam outlet from the middle compartment, a water inlet to each lower drum, a by-pass connection between the compartments of the upper drum, and valves controlling said by-pass connection and said water inlets, substantially as described. 60

2. A water tube steam boiler comprising two lower water drums with furnace between them, two upper steam and water drums parallel thereto but nearer together, a common steam drum between the two 65 steam and water drums, and steam pipes connecting the common steam drums with the two steam and water drums, each lower drum being connected to the opposite upper drum by transverse rows of inclined generating tubes crossing beneath the steam drum above the center of the furnace, longitudinal partitions dividing the steam drum into three compartments, superheating tubes connecting said compartments which tubes 70 lie over one set of generating tubes and cross the other set, and valved connections between said compartments and a valved water inlet connected to said tubes, substantially as described. 80

3. In a water tube steam boiler, a superheater comprising a steam drum subdivided into compartments, superheating tubes connecting said compartments, an external pipe connection between said compartments, a 85 water inlet pipe to said tubes, and interconnected valves respectively controlling the said external connecting pipe and said water inlet pipe, substantially as described.

Signed at Newcastle on Tyne England this 90 fourteenth day of November 1918.

ROBERT BAYLES ARMSTRONG.
